(57) **CLAIM**

The ornamental design for a videotelephony apparatus, as shown and described.

DESCRIPTION

FIG. 1 is a rear view of a videotelephony apparatus;
FIG. 2 is a bottom view thereof;

FIG. 3 is a front view thereof;

FIG. 4 is a left side view thereof;

FIG. 5 is a right perspective view thereof;

FIG. 6 is a right side view thereof; and,

FIG. 7 is a top view thereof.

The broken lines in the figures show portions of the videotelephony apparatus that form no part of the claimed design.

1 Claim, 7 Drawing Sheets
